Des. 238,092

Patented Dec. 16, 1975

238,092

CURTAIN PATTERN

Peter Eric Schroeder, Oberwil, near Brenngarten, Switzerland, assignor to Gardisette International AG, Lucerne, Switzerland

Filed May 10, 1974, Ser. No. 469,014

Claims priority, application Germany Nov. 12, 1973

Term of patent 14 years

Int. Cl. D5—02

U.S. Cl. D47—6 E

The single figure is a plain view of a curtain fabric showing my new design, the dark background being for purposes of illustration only.

I claim:

The ornamental design for a curtain pattern, as shown and described.
